Elmore Talbert Attorney

UNITED STATES PATENT OFFICE.

RUFUS C. CRANFORD, OF DE LAND, FLORIDA.

WINDOW-SHADE BRACKET.

1,391,528.

Specification of Letters Patent. Patented Sept. 20, 1921.

Application filed February 11, 1919. Serial No. 276,257.

To all whom it may concern:

Be it known that I, RUFUS C. CRANFORD, a citizen of the United States, residing at De Land, in the county of Volusia and State of Florida, have invented new and useful Improvements in Window-Shade Brackets, of which the following is a specification.

This invention comprehends generally improvements in that class of inventions known as shades, curtains and screens, and more particularly relates to a window shade bracket.

It is the principal aim and object of the present invention to provide a device of the above mentioned character designed from a single blank of sheet metal capable of being subsequently bent to the desired shape and engaged in position on a window casing in such a manner as to obviate the necessity of independent fastening devices.

More particularly this invention contemplates the provision of a device of the above mentioned character designed with lateral wings which are bendable to provide a trunnion supporting arm subsequent to the stamping of the device from a piece of material.

It is a more specific object of the present invention to provide a device of the above mentioned character wherein the trunnion receiving and supporting arms are bendable upon and braced by the body so as to increase the relative rigidity of the parts.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction hereinafter described and the scope of the application of which will be indicated in the appended claim.

The invention is clearly illustrated in the accompanying drawings, in which:

Figure 1 is a perspective view of one of the improved brackets.

Fig. 2 is a side elevation showing one of the brackets applied.

Fig. 3 is a plan view of the blank from which the bracket is formed, and

Fig. 4 is a sectional detail on line 4—4 of Fig. 1.

Similar characters of reference are employed in all of the above described views, 60 to indicate corresponding parts.

Referring now, more particularly, to the accompanying drawings there is provided an improved bracket formed from a single piece of sheet metal and comprising a substantially triangular body 1 from the upper wide edge of which extends a supporting flange 2 bendable on the crease 3 so as to project at right angles from the rear face of the body while the free edge of the flange 70 is formed at and medially of the side edges with a plurality of anchoring spurs 4 bendable downwardly on the creases 5 so as to be anchored in the window casing 6 as indicated, while also formed on the free edge of 75 the flange between the spurs 4 are lugs 7 which facilitate the supporting of the bracket in position, said lugs lying on the upper surface of the top of the casing when the bracket is in a position as shown in 80 Fig. 2.

Depending from the vertex of the body is an extension 8 while projecting from the opposite sides of the extension are laterally disposed wings generally designated 9. 85 These wings are bendable inwardly on the creases 10 to provide wing engaging portions 11, which act as braces, while the outer portions which provide arms 12, are subsequently bent outwardly on the creases 13 90 and lie at right angles with respect to the body or extension 8 and in juxtaposed relation with respect to each other, the upper edges near the free terminals of the said arms being provided with slots 14 adapted 95 to accommodate one of the trunnions of a shade roller, as is apparent. By the peculiar construction described it will be appreciated that the extension engaging portions 11 form braces for the arms for preventing vertical and lateral movement of the arms and assure of an effective mounting for the trunnion of the shade roller (not shown). When the spurs 4 are anchored in position, as shown in Fig. 2, the bracket 100 is firmly maintained in position, the supporting flange 2, of course, forming an effective bearing for preventing accidental move-

ment and for effectively supporting the bracket in its entirety.

What is claimed is:

A device for the purpose indicated formed
5 from a single blank of metal and consisting
of a triangular body having a right-angu-
larly disposed supporting flange at its
upper edge, the said flange being formed
with anchoring spurs at its edge, the body
10 being formed with a depending extension
at its vertex, the said extension having op-

positely disposed laterally extending wings
bent back on themselves, with those por-
tions adjacent their extremities lying against
each other and formed with shade roller 15
stud receiving sockets the connecting por-
tions of the wings forming shade roller sup-
ports and being disposed in planes at right
angles to the body.

In testimony whereof I affix my signature. 20

RUFUS C. CRANFORD.
